US00D765562S

(12) **United States Design Patent** (10) **Patent No.:** **US D765,562 S**
(45) **Date of Patent:** **** Sep. 6, 2016**

(54) **WHEELCHAIR ARMREST**

(71) Applicant: **Invacare International Sarl**, Gland (CH)

(72) Inventors: **Edward Dahlin**, Dio (SE); **Mats Feldt**, Almhult (SE); **Susanne Ek**, Malmo (SE); **Ulf Johansson**, Almhult (SE); **Henrik Flink**, Almhult (SE); **Christopher Holmqvist**, Almhult (SE)

(73) Assignee: **Invacare International Sarl**, Gland (CH)

(**) Term: **14 Years**

(21) Appl. No.: **29/502,239**

(22) Filed: **Sep. 12, 2014**

(30) **Foreign Application Priority Data**

Mar. 13, 2014 (WO) DM/083472

(51) **LOC (10) Cl.** **12-12**

(52) **U.S. Cl.**

USPC **D12/133**

(58) **Field of Classification Search**

USPC D12/131, 133

CPC A61G 5/00-5/14

(57) **CLAIM**

The ornamental design for a wheelchair armrest, as shown and described.

DESCRIPTION

FIG. 1 is a front perspective view of a wheelchair armrest of the new design;

FIG. 2 is a right side elevational view of the wheelchair armrest of FIG. 1;

FIG. 3 is a left side elevational view of the wheelchair armrest of FIG. 1;

FIG. 4 is a top plan view of the wheelchair armrest of FIG. 1;

FIG. 5 is a bottom plan view of the wheelchair armrest of FIG. 1;

FIG. 6 is a rear elevational view of the wheelchair armrest of FIG. 1;

FIG. 7 is a front elevational view of the wheelchair armrest of FIG. 1;

FIG. 8 is a front perspective view of a second embodiment of a wheelchair armrest of the new design;

FIG. 9 is a right side elevational view of the wheelchair armrest of FIG. 8;

FIG. 10 is a left side elevational view of the wheelchair armrest of FIG. 8;

FIG. 11 is a top plan view of the wheelchair armrest of FIG. 8;

FIG. 12 is a bottom plan view of the wheelchair armrest of FIG. 8;

FIG. 13 is a rear elevational view of the wheelchair armrest of FIG. 8; and,

FIG. 14 is a front elevational view of the wheelchair armrest of FIG. 8.

The dashed lined portions of the drawings indicate unclaimed subject matter that forms no part of the claimed design.

1 Claim, 14 Drawing Sheets
